[57] **CLAIM**

The ornamental design for a multi-function programmable electronic calculator, as shown and described.

DESCRIPTION

FIG. 1 is a top plan view of a multi-function programmable electronic calculator showing my new design;
FIG. 2 is a rear elevational view;
FIG. 3 is a right side elevational view;
FIG. 4 is a left side elevational view;
FIG. 5 is a front elevational view;
FIG. 6 is a bottom plan view;
FIG. 7 is a right, front and top perspective view thereof.

FIG.2

FIG.4

FIG.1

FIG.3

FIG.5

FIG. 6

FIG. 7
